UNITED STATES PATENT OFFICE

AMOS RANK, OF SALEM, OHIO.

DESIGN FOR GRAVE-GUARDS.

Specification forming part of Design No. 7,786, dated October 6, 1874; application filed August 28, 1874.
[Term of Patent 14 years.]

To all whom it may concern:

Be it known that I, AMOS RANK, of Salem, in the county of Columbiana and State of Ohio, have invented a Design for Grave-Guards, of which the following is a specification:

The nature of my invention is fully represented in the accompanying drawing, to which reference is here made.

The guard is nearly or quite flat as regards its upper and under surfaces, and in its external circumference it is approximately of oval shape, the end portions being formed on a short or acute curve, as from *a* to *a*, and the side portions on a longer curve, or on one much more nearly approaching a straight line, as at *b b*. The top or upper surface of the guard is narrower and shorter than the under side thereof, and consequently the cir-

cumferential surface is made flaring and sloping outward and downward, as fully shown in the drawing. The guard is hollowed out at its central part, as shown at *A*, so that it has more or less the form of an oblong or oval annulus, thicker horizontally at the ends than at the lateral portions, the form of the open space thus provided within the guard approximating in any desired degree to the outline of the guard.

What I claim as my invention is—

The design for a grave-guard in which the outer circumferential surface is of oval configuration, and flaring outwardly toward its base, as shown and described.

AMOS RANK.
